UNITED STATES PATENT OFFICE

DE WITT DOCKSTADER, OF JOHNSTON, NEW YORK

DEVICE FOR MEASURING THE INSEAMS OF MEN'S TROUSERS AND HEIGHT OF WAIST-BANDS

Application filed December 17, 1928. Serial No. 326,575.

The present invention relates to improvements in measuring instruments and has reference more particularly to a device for measuring the in-seam of a pair of trousers 5 in an accurate and efficient manner.

One of the important objects of the present invention is to provide a measuring device of the above mentioned character that includes a vertically movable crotch stick that carries 10 at its upper end a horizontally disposed crotch bar for fitting snugly in the crotch of the trousers when a person stands over the device, so that an accurate measure of the in-seam of the trousers may be obtained.

Still a further object is to provide a measuring device of the above mentioned character that has an attachment detachably associated with the crotch bar for determining the height of the trousers desired from the crotch 15 to the top of the waist band.

Still a further object is to provide a device of the above mentioned character that will at all times be positive and efficient in its operation, the same being further simple in 20 construction, inexpensive, strong and durable, and further well adapted to the purpose for which it is designed.

Other objects of the invention will become apparent as the nature of the invention proceeds and when taken in connection with the accompanying drawing.

In the accompanying drawing, forming a part of this application and wherein like reference characters designate like parts 25 throughout the several views:

Figure 1 is a front elevation of the measuring device showing the same in use.

Figure 2 is a side elevation thereof.

Figure 3 is a sectional view showing the 30 manner in which the crotch bar is slidably mounted in the slotted casing that is secured on the upper end of the vertical standard that projects from the top of the base or platform.

Figure 4 is a sectional view taken approximately on the line 4—4 of Figure 2, and

Figure 5 is a transverse section taken approximately on the line 5—5 of Figure 3.

In the drawing, wherein for the purpose of illustration is shown the preferred embodiment of my invention, the numeral 1 designates generally my improved measuring device, the same comprising a rectangular shaped base or platform 2, from which extends upwardly the standard 3, the lower end of said standard being formed with a reduced 55 portion 4 that fits within a suitable socket provided therefor in the base or platform. Reinforcing braces or brackets 5 extend between the upper face of the platform or base, and the opposite sides of the standard, as 60 more clearly disclosed in Figure 2.

A rectangular shaped casing secured on the upper end of the standard 3 is denoted by the reference character 6. The opposed sides of the casing are formed with longitudinally 65 extending slots 7, within which operates the pins 8, that project from the opposite side edges of the lower end portions of the crotch bar 9.

This crotch bar is formed with a longitudinally extending bore 10 that extends upwardly from the lower end of said crotch bar and operable within this bore 10 is the vertically disposed rod 11 that is anchored at its lower end within the upper end of the standard 3, said rod extending centrally 70 through the casing 6.

An expandable coil spring 12 is arranged within the casing and encircles the rod 11, said spring being disposed between the upper end of the standard 3 and the lower end of the crotch bar 9 for normally urging said crotch bar upwardly. The pins 8 cooperate with the slots 7 to prevent disengagement of the crotch bar from the upper end of the 75 casing.

Secured on the upper end of the vertically movable spring pressed crotch bar 9 is the horizontally disposed crotch engaging piece 13, the same being substantially triangular shaped in cross section as more clearly disclosed in Figure 4. This crotch engaging piece 13 is preferably secured adjacent its inner end on the upper end of the crotch bar or stick 9, in a rigid manner while the outer end portion of this crotch engaging piece 13 is provided with a longitudinally extending channel or groove 14, for removably receiving the tongue 15, that extends laterally from 80 85 90 95 100

50 In the drawing, wherein for the purpose of illustration is shown the preferred embodiment of my invention, the numeral 1 designates generally my improved measuring device, the same comprising a rectangular shaped base or platform 2, from which extends upwardly the standard 3, the lower end of said standard being formed with a reduced 55 portion 4 that fits within a suitable socket provided therefor in the base or platform. Reinforcing braces or brackets 5 extend between the upper face of the platform or base, and the opposite sides of the standard, as 60 more clearly disclosed in Figure 2.

the lower end of the vertically disposed scale or measuring stick 16.

A tape measure 17 of sufficient length is securely fastened at one end to the upper edge portion of the crotch engaging member 13.

In use, a person stands upon the base or platform 2, in such a position as to have a member 13 snugly fitting within the crotch portion of the trousers and the measuring tape 17 may be used by the tailor or other person taking the measurements for accurately measuring the inseam of the trousers, the tape measure being held in one hand while the trouser leg is held at the bottom in the other hand to insure the taking of the proper measurements.

The rod and spring will permit the crotch stick or bar 9 to move downwardly, in order that the device may be used to take an inseam measurement of either short or tall men.

The measuring rule 16 is used to obtain the height of the trousers desired from the crotch to the top of the waist band of the trousers, and the rule 15 with the tongue 16 associated therewith may be detached from the crotch engaging measure 13, when the rise of the trousers is not to be taken.

It will thus be seen from the foregoing description that I have provided a measuring device that will save considerable time and labor and will furthermore be accurate in obtaining the power measurement of the inseam of a man's trousers.

A device of this character will be strong and durable and can furthermore be constructed at a very low cost.

While I have shown the preferred embodiment of my invention, it is to be understood that various changes in the size, shape and arrangement of parts may be resorted to, without departing from the spirit of the invention or the scope of the appended claim.

I claim:

In a measuring device of the class described, a base, a standard extending upwardly therefrom, a guide rod secured at its lower end in the upper end of the standard, a casing encircling the rod and fixedly secured at its lower end on the upper end of the standard, the sides of the casing being formed with opposed longitudinally extending slots, a crotch stick arranged for slideable movement on the rod at the upper end of the casing, guide pins extending laterally from the opposite sides of the crotch stick for cooperation with the respective slots in the casing, and expansible coil springs arranged within the casing and encircling the rod for disposition between the standard and the crotch stick for normally urging the latter outwardly, and a crotch engaging member carried by the upper end of the crotch stick.

In testimony whereof I affix my signature.

DE WITT DOCKSTADER.
